UNITED STATES PATENT OFFICE.

ROBERT E. POWERS, OF MONTREAL, QUEBEC, CANADA.

COUPLING-CENTERING DEVICE.

1,421,556.

Specification of Letters Patent. Patented July 4, 1922.

Application filed December 3, 1920. Serial No. 428,019.

To all whom it may concern:

Be it known that I, ROBERT E. POWERS, a citizen of the United States of America, and resident of the city of Montreal, in the Province of Quebec and Dominion of Canada, have invented certain new and useful Improvements in Coupling-Centering Devices, of which the following is a full, clear, and exact description of the invention.

10 This invention relates to improvements in coupler centering devices, and the object of the invention is to provide a device of great simplicity and durability which will positively return a coupler from a position of lateral displacement to a predetermined position.

A further object is to provide a centering device enabling the use of a tie-bolt to strengthen the throat member through which 20 the coupler operates.

A still further object is to provide a centering device which will overcome the disadvantages inherent to roller centering devices.

25 Up to the present time a great variety of centering devices have been produced, a considerable number of which depend for their operation on one or more rollers interposed between a coupler carriage and a specially 30 formed track plate. These track plates slope upwardly from a central position and the centering device operates by reason of the rollers and carriage being forced upward on such track plate with the lateral movement. As the lateral movement is not very great and as the parts are subject to corrosion and accumulations of dirt it is necessary that the slope of the track be fairly sharp in order to ensure movement of the rollers, carriage and coupler to the lowest point. Such 35 sharply inclined track ways offer considerable resistance to the couplers.

According to the present invention, the coupler rests on a carriage which is in turn supported by a pair of rockers each having supporting points on opposite sides of the vertical centre. As a coupler is moved laterally, the carriage swings on the rockers at the same time raising the carriage and coupler. The only friction is at the ends of 50 the rockers and is much less than the friction of rollers.

In the drawings which illustrate the invention:—

Fig. 1 is an end elevation of the device. 55

Fig. 2 is a vertical sectional view.

Fig. 3 is a sectional view on the line 3—3, Figure 2.

Referring more particularly to the drawings, 11 designates the end sill of a car, to which is attached a throat plate 12 which in this invention is in the form of an inverted U-shaped casting defining a space 13 in which the coupler shank 14 may move horizontally and vertically. A pocket member 15 is mounted between the arms of the throat casting 12 and forms normally a support for the coupler shank. This pocket member is held in place by a bolt 16 which passes through it and through the arms of the casting 12 thus connecting the arms together and supporting them so that they will not be readily broken at their junction with the top member of the casting by pressure or pounding of the coupler against them. The bolt 16 is disposed midway between the front and back walls 17 of the pocket member, as clearly shown in Figure 3, but the weight of the centering device and coupler is supported by the lugs 11 of the throat plate independently of the bolt 16. The bottom of the pocket member is provided with a plurality of grooves 18 extending parallel with the coupler shank, these grooves being preferably four in number as shown in Figure 2. The bottom of the pocket is also provided with an outlet 19 for the escape of water and cinders which may become lodged therein.

In the upper part of the pocket member a carriage 20 is provided having upstanding flanges 21 at its ends which embrace between them the coupler shank. The lower surface of this carriage is provided with a plurality of grooves 22 similar to the grooves 18 and preferably disposed vertically above and parallel with the same.

One or more rockers 23 are disposed between the bottom of the pocket member and the carriage to support the latter. Each rocker has two points of support 24 at the bottom spaced equidistant on opposite sides of the vertical axis indicated by the section line 3—3. The top of the rocker is of exactly the same construction as the bottom, having four points or lugs 24 to support the carriage. Preferably the top and bottom of the rocker have the same dimensions in every respect so that it can be inverted at

will. These points or lugs 24 bear in the grooves 18 and 22 of the pocket and carriage respectively. For convenience and to provide for the passage of the bolt 16, the rockers are preferably each formed of two similar plates 25 connected intermediate the top and bottom by a cross member 26, so that each rocker when viewed edgewise is in the form of a letter H, as clearly shown in Figure 3.

The rockers normally stand on both points of support so that their axes are vertically disposed, as shown in full lines Figure 2. In this position the carriage is supported equally on the top points of each rocker and the load being applied squarely over the points of support at the bottom, the rocker has no tendency to swing about either point of support. As a car travels over a curve the couplers are drawn laterally out of the axial line of the car so that the shanks travel to one side or the other of the opening 13 of the throat plate. As a coupler moves laterally it draws the supporting carriage 20 with it and the carriage, if in engagement with each rocker, swings the rocker about two of its points of support on the bottom of the pocket. Owing to the engaging points 24 of the rocker being on opposite sides of the vertical axis at both top and bottom, it is obvious that the swing of the rocker about either point of support at the bottom will raise the point of support on the opposite side of the axis at the top, as clearly shown in broken lines Figure 2. The load line is thus immediately shifted out of parallelism with the vertical axis and is represented by a diagonal of the rocker. It will be also seen that the application of coupler weight at the top of the rocker at one end of the load line is considerably to one side of the pointed support at the bottom of the rocker and at the opposite end of the load line so that the tendency is for the rocker to return to normal position of support on both bottom points 24. As long as the load line remains on one side of the vertical from the point of support the rocker will return to normal. The width of the opening 13 is such that the rockers cannot be swung sufficiently to bring their load lines to the verticals above the points of support, so that the rockers tend always to resume their original position. The upward movement of the carriage supporting points of the rockers raises the carriage and therefore the coupler thereon, so that the whole weight of the coupler carriage and rockers is effective to return the rockers to their normal position in which they swing the coupler between the sides of the opening 13 and in the central axis of the car.

The rockers impart a much greater elevating movement to the carriage and

coupler than is possible by the use of rollers on inclined tracks without making the inclination of the tracks so great as to offer considerable resistance to the lateral movement of the coupler. Rollers have been found to have a strong tendency to become fixed in their bearings or fixed to one of the relatively moving members, so that they would be compelled to slide in place of roll as intended. In the present construction these conditions cannot occur as the rockers do not move bodily but merely swing about their points of support. As will be noted in Figure 2, the rockers occupy the whole bottom of the pocket so that they cannot jump out of the grooves and assume improper positions. In the same way the carriage cannot jump the rockers and assume an improper position as it is retained by the depending end flanges 27. There is no room for the rockers to fall over laterally as the end walls of the pocket prevent this while the front and back walls prevent any upsetting in the longitudinal direction of the car. The bridge 28 provided in the centre of the pocket member not only strengthens the pocket member by spanning the drainage outlet 19 but also prevents either of the rockers from fouling the other rocker and interfering with the free operation thereof. The rockers being exactly the same, top and bottom, it is impossible for them to be put in incorrectly. When once in place both are retained by the bolt 16 which passes between the plates 25 thereof.

While the invention as thus far shown and described concerns only rockers which bear at their ends in recesses, it will be understood that they are in effect links and that the same result would be obtained if the rockers were formed with notches or grooves to receive ribs or pins carried by the pocket member and carriage. In other words, the invention is not limited to the precise shape of the rocker illustrated, as a number of modifications may be made therein without departing from the spirit of the invention. It will be seen that the same result can be obtained if the rockers are definitely pivoted to either the pocket or the carriage. In such an arrangement the rockers might be termed links. It is to be understood that the term "rocker" as used in the following claims is generic and includes any element disposed in the manner and performing the functions described. While the invention has been illustrated with two rockers it will be understood that a greater or lesser number of rockers may be used.

Having thus described my invention, what I claim is:—

1. A coupler centering device comprising a U-shaped throat, a coupler support con-

1. nected between the arms of the throat, a 45
coupler supporting carriage, rockers sup-
porting the carriage on the support, and a
bolt connecting the arms of the throat and
holding the support and the rockers.
2. In a coupler centering device, a U-
shaped throat member, a coupler support
mounted between the arms thereof, a cou-
pler centering device mounted on said sup-
port, and a bolt connecting the arms of the
throat and holding the centering device
against dislodgment. 50
3. In a coupler centering device, a cou-
pler support having a pocket therein, a car-
riage in said pocket engaging the coupler
and rockers in said pocket supporting the
carriage, each of said rockers comprising a
pair of spaced plates and a bridge connect-
ing said plates intermediate their ends. 55
4. In a coupler centering device, a pocket
member forming a coupler support and pro-
vided with grooves in its bottom, a coupler
carriage mounted in said pocket and also
provided with grooves in its bottom, a rocker
disposed between the pocket bottom and cou-
pler bottom comprising a pair of spaced
plates each bearing in two grooves of the
pocket and in two grooves of the carriage,
and a bridge connecting said plates. 60
5. A coupler centering device comprising
a throat member presenting spaced arms, a
pocket member forming a coupler support
and provided with aligned bolt openings, a
bolt passing through said arms and through
the openings in said pocket member, a cou-
pler carriage mounted in the pocket member
and a rocker interposed between said car-
riage and the bottom of the pocket member
and provided with a passage aligning with
the openings in the pocket member and re-
ceiving the bolt therethrough. 65
6. In a coupler centering device, a mem-
ber forming a coupler support, a coupler
- carriage disposed above the support and a
rocker disposed between the coupler sup-
port and carriage presenting spaced sup-
porting points at its upper end in rolling
contact with said carriage on opposite sides
of the longitudinal center of the rocker and
similar supporting points at its lower end in 50
rolling contact with the coupler support,
and projections from the support and car-
riage respectively, fitting into the space be-
tween the spaced points of support in con-
tact therewith and providing fulcrums for 55
the rocker. 55
7. In a coupler centering device, a rocker
for interposition between the coupler sup-
port and carriage comprising a body having
spaced supporting points projecting longi-
tudinally beyond each end thereof and on
opposite sides of the longitudinal center of
the body, the supporting points at one end
of the body being aligned longitudinally
with the supporting points at the opposite 60
end. 60
8. The combination with a rocker accord-
ing to claim 8 of a coupler carriage grooved
for interfitting rolling contact with the up-
per end of the rocker and a coupler sup-
port grooved for interfitting rolling con-
tact with the lower end of the rocker. 70
9. A coupler centering device, comprising
a coupler carriage, a support therefor,
the opposing surfaces of the support and 75
carriage being grooved, and a reversible
rocker interposed between said carriage and
support and provided at its ends with pro-
jections engageable in said groove, the pro-
jections at each end of the rocker being 80
adapted for engagement either with the
grooves of the support or of the carriage.

In witness whereof, I have hereunto set
my hand.

ROBERT E. POWERS.
